ATTORNEY

UNITED STATES PATENT OFFICE.

GEORGE ALFRED HERTLEIN, OF PUEBLO, COLORADO.

VISE.

985,807.

Specification of Letters Patent. Patented Mar. 7, 1911.

Application filed November 20, 1909. Serial No. 529,118.

To all whom it may concern:

Be it known that I, GEORGE ALFRED HERTLEIN, a citizen of the United States, and a resident of the city of Pueblo, in the county 5 of Pueblo and State of Colorado, have invented a new and useful Improvement in Vises, of which the following is a specification.

The principal object of my invention is 0 to provide a portable and durable vise, supported on a suitable frame, and operated by means of foot power.

In the drawing—Figure 1 is a side view 5 of the mechanism, with parts broken away to show ratchet arrangement on the same. Fig. 2 is a front view of the mechanism.

Similar numbers refer to similar parts in all the figures of the drawings, and the various parts may be made of any suitable material.

Frame 1 is securely supported by legs 6 bolted or otherwise fastened thereto. To this frame 1, a stationary head or jaw 2 is secured by bolts or otherwise. Through an opening in jaw 2, passes the movable jaw 3, formed with ratchet teeth as shown. Passing through movable jaw 3 is mandrel 4, operated by handle 5. Hand lever 7 is pivoted in the main lever 10 for depressing toothed movable block 8, which is seated on spring 14, in the upper end of main lever 10, and which is adapted to interlock with ratchet teeth in movable jaw 3. An eyebolt or other suitable means secures spring 9 at its upper end to frame 1, and by proper means, spring 9 is attached at its lower end to a knuckle joint, which is connected with foot lever 13 by hanger 15. Main lever 10 is supported by frame 1 and fulcrumed on main pin 13 passing through frame 1, and is attached at its lower end to knuckle joint 11.

In operation, foot pressure is applied to foot lever 12, and thereby knuckle-joint 11 and foot lever 12 are both forced from the 45 position shown approximately by the dotted line until main lever 10 takes the position about similar to position as shown in Fig. 1. As pressure is thus applied, movable jaw 3 is constantly or gradually, as desired, 50 forced by means of the ratchet nearer and nearer to stationary jaw 2, thereby giving pressure suitable to any work required. Should it be desired to release jaw 3, after being forced toward jaw 2 and locked by 55 the ratchet, lever 7 may be raised by suitable pressure, thereby forcing down toothed block 8, until the same is free from movable jaw 3. Lever 10 is provided with ratchets at the lower end thereof and a suitable stop, 60 as shown in Fig. 2. Foot lever 12 is made in such manner that it may be interlocked with ratchets on main lever 10 at any time desired, or released by pressure downward 65 and away from the ratchets.

Having thus fully described my invention, what I claim as new and desire to secure by Letters Patent is:—

In a vise, the combination of the frame, the main pin, the fixed jaw, the movable 70 jaw formed with ratchet teeth, the foot-lever, the main lever connected thereto and fulcrumed on the main pin, the toothed movable block seated in the upper end of the main lever, and the hand lever pivoted in 75 the main lever for depressing the toothed block, and the spring for pressing the block upward to engage the movable jaw; substantially as described.

GEORGE ALFRED HERTLEIN.
